(57) **CLAIM**

The ornamental design for a rotary switch for automobile, as shown and described.

DESCRIPTION

FIG. 1 is a perspective view of a rotary switch for automobile showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines depict a portion of the switch, which form no part of the claims.
